UNITED STATES PATENT OFFICE.

SEWELL E. WINSLOW, OF BRIDGEPORT, CONNECTICUT.

COMBINED SHAFT-TUG AND BUCKLE.

No. 910,759.

Specification of Letters Patent.

Patented Jan. 26, 1909.

Application filed September 26, 1908. Serial No. 454,920.

To all whom it may concern:

Be it known that I, SEWELL E. WINSLOW, a citizen of the United States, residing at Bridgeport, county of Fairfield, State of Connecticut, have invented a new and useful Combined Shaft-Tug and Buckle, of which the following is a specification.

This invention has for its object to provide a metallic shaft tug and buckle, all the parts of which may be cast integral with the exception of the buckle tongue which is detachable. I am thus enabled to produce shaft tugs very much cheaper than leather tugs can be produced, which may be made as highly ornamental as the finest leather tugs, which will permit the shafts to slide freely therein thus preventing movement of the saddle and facilitating the detachment of the shafts from the tugs in unharnessing, and which shall be practically indestructible.

With these and other objects in view I have devised the novel combined shaft tug and buckle of which the following description in connection with the accompanying drawing is a specification, reference characters being used to indicate the several parts:

Figure 1 is an elevation illustrating my novel metallic tug and buckle in place upon a tug strap as in use; Fig. 2 a longitudinal section corresponding with Fig. 1; Fig. 3 a detail sectional view on the line 3—3 in Fig. 2 looking in the direction of the arrows; and Fig. 4 is a detail sectional view on the line 4—4 in Fig. 2, looking in the direction of the arrows.

It is of course well understood that the shaft tugs in ordinary use are made of leather, are made part of the girth and are attached to the tug strap by means of a buckle, the retaining loop for the end of the tug strap being of leather and stitched to the tug. This construction is expensive to produce and is subject to wear, my novel combined tug and buckle being inexpensive to produce, equally ornamental with a leather tug and practically indestructible.

The present invention comprises essentially an oval body indicated by 10 which receives the thill or shaft of a wagon, a buckle frame indicated by 11, a tug strap loop indicated by 12 and a girth loop indicated by 13. These parts are all cast integral. The buckle frame consists of arms 14 which extend from the upper end of the body on opposite sides thereof, the outer ends of said arms being connected by a cross piece 15. The body is

provided on one side with a central longitudinal slot 16 which extends approximately to the top of the body terminating between the arms of the buckle frame. At the lower end of this slot is an opening 17 of greater length than width.

18 denotes the buckle tongue, the outer end of which is adapted to engage cross piece 15. At the inner end of the tongue is a cross arm 19 of greater length than the width of opening 17. This cross piece in use lies on the inner side of the body. The tongue is also provided with an oblong plate or enlargement 20, which lies on the outer side of the body and when placed in longitudinal alinement with opening 17 will pass freely therethrough and when placed transversely to said opening and to slot 16, which is its normal position, will retain the tongue in place in the body. Intermediate the cross arm and plate 20 the tongue is provided with an angular neck 25 which fits closely enough in slot 16 in the body to render it impossible for the tongue to turn. The tug strap loop which is cast integral with the body is placed upon the outer side of the body in suitable position to receive and retain the lower end of the tug strap after it has been buckled to the tug. The girth loop, which is also cast integral with the body, is placed at the lower end thereof in suitable position for the attachment of the girth (not shown).

23 denotes a tug strap and 24 a hole therein for the buckle tongue. In order to furnish a finer finish for shaft tugs used upon high grade harnesses, I provide face plates 21 for the cross piece of the buckle and for the tug strap loop, said face plates being made of relatively high grade metal which may be plated and will receive a high polish. These face plates are made self-attaching by means of integral lugs 22 which are clamped on the under side of the cross piece of the buckle frame and the under side of the tug strap loop and retain the face plates securely in place.

The operation will be readily understood from the drawing. In attaching my novel shaft tug to a tug strap, the end of the strap is passed downward through the buckle frame back of the cross piece and through the tug strap loop. The buckle tongue is inserted from the inner side. The tug strap is passed downward far enough to place the tongue hole in central alinement with the opening 17 in the body. Plate 20 on the

tongue is then placed in longitudinal alinement with said opening and passed through the opening, after which, by means of the cross piece, the tongue is given a quarter turn placing cross arm 19 and plate 20 transversely to the slot 16 and opening 17. The tug strap is then drawn upward or the tug pulled downward, which will cause the neck of the tongue to slide along to the upper end 10 of the slot, in which position the parts will be locked as clearly shown in Fig. 2, the cross arm preventing the possibility of the tongue being drawn outward, neck 25 preventing it from turning and plate 20 preventing it from 15 being pushed inward. To detach the tug from the tug strap, the strap is pushed downward or the tug is raised relatively thereto sufficiently to move the neck of the tongue backward in slot 16 until plate 20 is in central 20 alinement with opening 17 in the body. The neck is now out of the slot so that the tongue may be given a quarter turn by means of the cross arm and readily drawn out, plate 20 passing freely through the opening 25 in the body.

Having thus described my invention I claim:

1. A combined shaft tug and buckle comprising a body adapted to receive a shaft and

having a longitudinal slot and an elongated 30 opening at the lower end of the slot and a buckle tongue having at its inner end a cross arm adapted to engage the inner side of the body and an oblong plate adapted to be passed through the opening when in alinement therewith and to normally lie on the outer side of the body to retain the tongue in place after the tongue has been given a quarter turn and has passed into the slot.

2. A combined shaft tug and buckle comprising 40 a body adapted to receive a shaft and having a longitudinal slot and an elongated opening at the lower end of the slot and a buckle tongue having at its inner end a cross arm adapted to engage the inner side of the body, an oblong plate adapted to be passed through the opening when in alinement therewith and an angular neck between the cross arm and the plate which engages the slot and prevents the tongue from turning 45 when in the operative position.

In testimony whereof I affix my signature, in presence of two witnesses.

SEWELL E. WINSLOW.
